FOLDAWAY BENCH-TABLE SHIPPING-STORAGE UNIT

Frederick C. Thompson, Washington, D. C., assignor to Converti-Bench Corporation, Washington, D. C., a corporation of Delaware

Application July 22, 1952, Serial No. 300,310

6 Claims. (Cl. 155—43)

The present invention relates to a dual purpose piece of furniture and more particularly to a piece of furniture usable either as a bench or bench-table and foldable into a compact box-like form free from external surface deformations likely to interfere with ready storing and stacking when not in use.

The present invention constitutes an improvement in bench-table furniture combinations of the general type disclosed in United States Letters Patent 1,792,737, issued February 17, 1931, to Milfred L. Greenstreet and 2,509,556, issued May 30, 1950, to Ralph H. Zimmerman, John M. Gordon and the present applicant. Devices of this character are most useful in picnic areas of public parks and field use by Army and like units or motion picture companies when on location in shooting pictures and in school, or like buildings to furnish a large room provided for multi-purpose use as a gymnasium, auditorium and lunch room as needs dictate. This furniture piece also provides an excellent piece of yard furniture for the home owner interested in outdoor barbecue pits and backyard picnics. To properly serve all of these purposes, a neat, sturdy but compact foldaway unit is highly desirable to withstand the repeated handling in such building use, outdoor use and for storing and transportation purposes yet easy operation. In addition, the parts should be readily assembled in manufacture to minimize cost and all parts should preferably be permanently attached to the seat or back-table boards and devoid of removable nuts, bolts and the like that may be easily misplaced or lost.

It is, therefore, the primary object of this invention to provide a dual purpose bench, bench-table construction which is sturdy, stable, and easily operable in changing from one use to another and in setting up and dismounting yet which in its foldaway condition provides an easily handled, readily stackable storage unit.

A further important object of this invention resides in providing a dual purpose bench, bench-table with a minimum of normally separable parts which may be easily and quickly swung from a stored position to a usable position or vice versa.

Another object of this invention is to provide a main leg support structure of simple planar form that may be readily produced with a minimum of manufacturing equipment and attached in place for easy manipulation between stored and supporting position.

A still further object of the present invention is to provide a back-table board support structure of simple form that will effectively support the back-table board in either its bench back or table top positions and still be attached in place for easy manipulation between stored and supporting position.

A further object of the present invention resides in the provision of a novel seat board assembly and a novel back-table board assembly formed along their longitudinal edges with relatively wear resistant, reinforcing portions which define between them a storage recess for the respective support structures and are arranged to

2

abuttingly engage in stored position to provide a box-like unit having outer faces free of projections and suitable for level stacking either on edge or on their major faces.

Still another object of the present invention resides in the provision of a back-table board assembly having permanently attached support posts designed to support the back-table board either in bench back or table top position in transverse alignment with the seat board.

Another object of the present invention resides in providing a support structure mounting assembly for a bench, back-table, including a universal connecting member, that may be readily prefabricated and assembled in place on seat boards or back-table boards of varying length without the need of performing special assembly operations on the seat or back table boards.

A further object of the present invention resides in providing a novel universal joint connection for a bench, bench-table of simple yet sturdy and reliable construction.

Still another object of the present invention resides in providing bench leg support reinforcing rods with novel adjustable ball engaging sockets at one end and novel leg connections at the other thereby adapting said rods for permanent adjustable connection to the seat board and ready association with the leg supports.

Further objects will appear from the following detailed description when read in conjunction with the appended claims and attached drawings wherein:

Figure 1 is a perspective view illustrating the storage unit provided by the bench, bench-table construction of this invention;

Figure 2 is an end view on an enlarged scale of the storage unit of Figure 1 as viewed from the left end of Figure 1;

Figure 3 is an end elevational view of the bench, bench table of this invention in its assembled condition showing the back-table board in solid lines in bench-back position and in dot-dash lines in table top position;

Figure 4 is a rear view of the bench, bench-table of this invention as seen from the right of Figure 3;

Figure 5 is an enlarged detailed sectional view taken on line 5—5 of Figure 1 and illustrating the novel support structure mounting assembly and novel universal joint connection of the present invention;

Figure 6 is an enlarged detailed sectional view taken on line 6—6 of Figure 3 and illustrating the manner of securing the novel leg support structure in supporting position;

Figure 7 is a bottom plan view of the seat board assembly of the present invention showing how the leg structures and leg reinforcing rods are connected thereto and stored therein;

Figure 8 is a bottom plan view of the back-table board assembly of the present invention showing how the support posts are connected thereto and stored therein;

Figure 9 is an enlarged sectional view taken on line 9—9 of Figure 7 and illustrating the novel adjustable ball engaging sockets provided on the attached ends of the seat board leg support reinforcing rods;

Figure 10 is an enlarged sectional view taken on line 10—10 of Figure 3 illustrating the novel leg connections provided on the opposite ends of the seat board leg support reinforcing rods; and

Figure 11 is a fragmental rear view of a bench, bench-table of this invention illustrating a modified back-table board support post designed to assure transverse alignment of the back-table board and seat board when the back-table board is disposed in position to serve as a bench back, the dot-dash line illustration depicting the stored position of the modified support post.

With continued reference to the drawings wherein like parts or elements in the various views are designated by the same reference numerals, the numeral 15 indicates the storage or shipping unit provided by the bench, bench

table of this invention when disposed in its foldaway condition. Referring for the moment to Figures 1 and 2, of the drawing, storage or shipping unit 15 is composed of a combined bench board-table board assembly 16 and a seat board assembly 17 secured together at their four corners by respective two part separable fasteners 18 preferably disposed on the inside faces of edge walls 19 and 20 of the storage unit. While fasteners 18 may be of any suitable construction, they preferably take the form of the well known two part trunk type fastener made up of a rigid hook element 21 connected preferably to assembly 16 and pivoted clasp element 22 connected preferably to assembly 17. Such fasteners in operation draw the respective assemblies to which they are secured toward each other under considerable force to secure them in unitary connected relationship in well known manner. If desired, the abutting edges of assemblies 16 and 17 may be matingly rabbeted (not shown) to positively retain the assemblies against sidewise dissociation.

As clearly seen from Figures 1 and 2, edge walls 19 and 20 of unit 15 as well as the exposed seat board and back board surfaces are free of external protuberances. Consequently, the storage or shipping units 15 may be safely stored on any of its four sides without danger of tipping over and stacked one upon the other in stable level piles.

In order to obtain this desirable smooth surfaced rectangular storage and shipping unit, the present invention contemplates a novel construction of the seat board assembly 17 and a novel back board-table board assembly 16 constructed to respectively effectively house the seat board leg support structure and the back board-table board support structure and receive between them a seat board cushion 23, when such a cushion is supplied.

Referring first to the seat board assembly 17 and to Figures 2, 3, 4 and 7 in particular, seat board assembly 17 comprises a seat board 24 preferably made of $\frac{5}{8}$ inch fir plywood of 8, 10 or 12 foot length as desired, allowing 2 feet of seating per person, and a width of $17\frac{1}{2}$ inches. The longitudinal edges of seat board 24 are suitably reinforced to prevent sagging in use by longitudinally extending reinforcing strips 25 preferably of 1 inch by $2\frac{3}{4}$ inch fir rabbeted at 26 (Figures 1 and 2) to receive the longitudinal marginal edges of seat board 24. Strips 25 at the upper outer edges adjacent the rabbeted portions 26 are rounded as indicated at 27 to prevent splintering and provided rounded seat edges for comfort. While any suitable means of securing strips 25 to seat board 24 may be employed, the present invention contemplates a nailed and glued joint utilizing any suitable waterproof adhesive.

As clearly seen in Figure 2, strips 25 depend below face 28 of seat board 24 approximately $2\frac{1}{8}$ inches defining with face 28 an open sided, open ended recess 29. Recess 29 is of sufficient depth to receive the seat board leg support structure comprising respective leg support assemblies 31 located preferably inwardly of the opposite ends of seat board 24 and most of cushion 23. For economy, ease of manufacture and long life when exposed to the elements, each assembly 31 comprises a leg structure of tubular steel or aluminum. Each assembly is made up of a long length of $1\frac{1}{8}$ inch outer diameter cold rolled tubing 32 having a front substantially vertical section 33 having its upper end terminating approximately $13\frac{3}{8}$ inches above ground level.

Vertical section 33 at its lower end is bent rearwardly on a 3 inch radius to provide an inclined portion 36 disposed at an angle of approximately 82° to vertical section 33 to provide a front ground engaging section or foot 37. At its rear end, section 36 is bent downwardly on a 3 inch radius through an angle of $12^\circ 30'$ to provide a horizontal section 38 spaced above ground level. The rear end of section 38 is in turn bent downwardly around a 3 inch radius through an angle of $12^\circ 30'$ to form a

second oppositely inclined section 39 the lower end of which is in turn bent upwardly around a 3 inch radius through an angle of 156° to provide a forwardly and upwardly inclined section 41. The inclined section 41 terminates short of contact with horizontal tube 48 and is flash welded as indicated at 42 to a rearwardly inclined reinforcing tube 43 of $1\frac{1}{4}$ inch outer diameter provided also to serve as a socket for the support posts or legs of the back board-table board assembly 17. Tube 43 at its lower end is flash welded as indicated at 44 to horizontal section 38 of tube 32 and preferably is inclined rearwardly to form an angle C of approximately 75° to the horizontal. A gusset plate 45 is flash welded as indicated at 46 to the tubes 32 and 43 at the apex of the forwardly facing angle formed therebetween. Gusset plate 45 is provided with a through drilled aperture 47 of $\frac{5}{8}$ inch diameter for a purpose to be presently pointed out.

It will be appreciated that the uniform radii of the various bends in tube 32 provides for a minimum of bending equipment and greatly reduces the chances of error in production. Preferably a tube 32 of suitable length to assure a finished front to rear dimension of $26\frac{1}{4}$ inches is utilized to assure stability of the bench-table when in use. While the various bends may be formed in any convenient order, it has been found desirable to first provide the desired bends at each end of section 38 and then bend the front section 33 and the rear section 41.

The leg support assemblies 31 are completed by horizontally disposed mounting tube 48 of 1 inch outer diameter fitted with a journal sleeve 49 encircling tube 48 adjacent its rear end. Sleeve 49 is located axially of tube 48 by $1\frac{1}{8}$ inch outer diameter retainer rings 51 and 52 disposed respectively at the front and rear ends of sleeve 49. The location of sleeve 49 is predetermined by locating retainer ring 51 a distance of $10\frac{1}{2}$ inches from the front end of tube 48 and tack welding the ring to tube 48. The second retainer ring 52 is then disposed against the rear end of sleeve 49, sufficient clearance being provided between the sleeve and rings to assure free journalling of tube 48 in sleeve 49, and tack welded to tube 48. The front peripheral end of tube 48 is then flash welded as indicated at 53 to the upper end of vertical section 33 of tube 32 and its rear end is flash welded as indicated at 54 to the front face of tube 43.

As clearly shown in Figure 5, sleeve 49 at one side is provided with a right angularly disposed boss 55 the free end of which is formed with a cylindrical journal portion 56 of reduced size. While boss 55 may be provided in any suitable manner, the present invention contemplates a solid cylindrical element having a curved seat 57 formed to closely fit the periphery of sleeve 49 and flash welded thereto at 58.

The reduced portion 56 of boss 55 is disposed in an aperture 59 formed in predetermined position in a mounting plate 61 and has a journalled fit therein. While plate 61 may assume any suitable form and aperture 59 may be suitably located therein, it has been determined that a mounting plate of 12 gauge rolled steel 14 inches long and six inches wide with aperture 59 located $2\frac{1}{4}$ inches inwardly from longitudinal edge 62 (Figure 7) and $\frac{1}{2}$ inch from one end is particularly suitable. Such a plate drilled at four spaced points along each side $\frac{1}{2}$ inch inwardly of its longitudinal edges to receive mounting rivets and provided with two transversely spaced drilled holes located $2\frac{3}{4}$ inches from the end opposite that containing aperture 59 and respectively $\frac{1}{2}$ inch and $1\frac{1}{4}$ inches inwardly from edge 62 provides a universal mounting plate for either the right or left leg support assembly merely by reversing the faces as will be apparent from Figure 7.

Plates 61 are distinguishable as rights and lefts only by the manner in which the leg securing clips 63 are

attached thereto. In this connection, a left plate (left and right having reference to the plate locations in Figure 7) has clip 63 secured to one face by suitable rivets 64 passing through the mounting leg of clip 63 and the transversely spaced drilled holes heretofore mentioned while the right plate has the clip 63 similarly mounted on the opposite face of plate 61.

Plates 61 are preferably mounted in place to complete the assembly 31 by placing them clip face down on bosses 55 with reduced journal portion 56 extending through aperture 59 and projecting away from the plain face of plate 61 and flash welding a retaining washer 65 (Figure 5) to the projecting end of portion 56 as indicated at 66. It is to be understood that washer 65 is axially spaced along reduced portion 56 sufficiently to assure relative rotative journaling movement between plate 61 and the boss 55 and washer 65 as a unit. This journaling movement in conjunction with the journaling movement of tube 48 in sleeve 49 constitutes a universal connection fabricated as a part of leg support assemblies 31 and adapts these prefabricated assemblies 31 for ready unitary mounting in desired position upon seat board 24.

While clips 63 are provided primarily to stop leg support assemblies in their proper support position when in use, clips 63 are preferably adapted to also provide a strong holding function to aid in assuring that assemblies 31 will not fail in use. To this end, clips 63 are formed of $\frac{3}{16}$ inch by 1 inch spring steel having a flat securing section 68 terminating at one end in a partial loop 69 (Figure 6) having an internal diameter of 1 inch and extending from its juncture with section 68 through slightly more than 180° and terminating with a terminal tip 71 extending away from said loop end divergently with respect to section 68. Tip 71, due to its divergency with respect to section 68 provides an outwardly flaring entryway for tube 48 when the tube 48 swings toward support position and cams the free end of loop 71 away from section 68 to permit entry of tube 48 into loop 69. After tube 48 reaches home position in loop 69, the resiliency of clip metal causes the loop to tightly grip tube 48 and the juncture of loop 69 and tip 71 is resiliently held at a level slightly inwardly of a plane tangent to tube 48 and paralleling section 68 of clip 63 to resilient lock the swingable leg portion in supporting position.

To facilitate ready assembly of leg support assemblies 31 on face 28 of seat board 24 in proper transverse position, the present invention provides spacers 73 in the form of fir plywood strips of 6 inch width and a length just sufficient to closely fit lengthwise between reinforcing strips 25, in the illustrated embodiment a length of $15\frac{1}{2}$ inches. Spacer strips 73 are each provided with a $1\frac{1}{4}$ inch drilled hole 74 centered $2\frac{1}{4}$ inches inwardly from a longitudinal edge and 13.94 inches from the front end of the strip (the term front end having reference to the left end of seat board 24 as seen in Figure 3). At the time the $1\frac{1}{4}$ inch hole is drilled spacer strips 73 are also provided along each longitudinal edge with four drilled holes centered $\frac{1}{2}$ inch in from the respective longitudinal edges and longitudinally spaced 4.33 inches apart to correspond in location to the spacing of the rivet holes in plate 61. Thus, when spacers 73 are located in position snugly between reinforcing strips 25 at the desired point longitudinally of seat board 24, they automatically predetermine the proper transverse as well as longitudinal location of the leg assemblies 31.

Mounting of the leg assemblies on seat board 24 is readily completed by drilling seat board 24 to receive the assembly rivets 75 (Figure 7) using the predrilled holes in spacers 73 as a guide.

Each of the spacers 73 and the seat board 24 immediately above them adjacent the back edge are provided with a $1\frac{1}{4}$ inch back-table support post hole 76 (Figure 5). As clearly seen from Figure 5, these holes 76 are

inclined and formed partly in the strip 25. They therefore cannot be conveniently drilled from the underside of the seat board though they must be accurately located with respect to the leg mounting structure on the underside of the seat. To assure proper location, holes 76 are preferably formed by first locating their centers in the top surface of the seat board through a counterboring operation from the underside with a very small centering drill. The centering drill is accurately positioned by locating a point on each spacer 73 at a distance $1\frac{3}{4}$ inches rearwardly of the intersection of the wall of hole 74 with a plane containing the axis of hole 74 and extending in a direction parallel to the side edges of the spacers 73. The centering drill is then placed on this point of intersection, tilted in the aforesaid plane in the direction of hole 74 to an angle of 75° with respect to the plane of the face of the spacers and a centering hole is then drilled through the spacer and the seat board. Using this located center and a $1\frac{1}{8}$ inch drill starting in the top of seat board 24, the hole 76 may be readily and accurately drilled in the desired position and at the proper angle as shown in Figure 5. The top surface of seat board 24 is preferably spot faced to a depth of $\frac{1}{40}$ of an inch as indicated at 77 around hole 76 and brass bushing 78 of $1\frac{1}{8}$ inch outer diameter, $\frac{1}{40}$ inch wall thickness and having a C-shaped flange 79 (Figures 5 and 7) is inserted from the underside of the top through hole 76. The upper protruding end of bushing 78 is then spun over to provide a securing flange 81 (Figure 5) seated in spot faced recess 77.

With the drilling completed, the leg support assembly is then placed in position with washer 65 and the end of reduced portion 56 disposed in spacer hole 74. The rivet holes in plate 61 are then lined up with the rivet holes in spacer 73 and seat board 24 and rivets 75 are set to secure leg support assemblies 31 permanently to seat board 24. This mode of assembly permits accurate prefabrication of leg support assemblies 31 by quantity production methods and the adoption of accurate assembly line techniques to assembly of the leg support assemblies.

When assembled as heretofore described, leg support assemblies 31 may be readily disposed in stored position between seat board reinforcing strips 25 merely by swinging the leg assemblies around the journal axis provided by journal portions 56 or bosses 55 and then swinging the leg support structures downwardly around the journal axis provided by tubes 48 and sleeves 49. To retain the leg support structures in stored position, the plates 61 adjacent clips 63 are preferably provided with spring metal securing clips 82 (Figure 7). Clips 82 may take any suitable form but preferably constitute upstanding U-shaped clips riveted to plates 61 by rivets (not shown) passing through the bridge portion of the U-shaped clips.

The present invention also contemplates leg reinforcing rods 85 permanently mounted on face 28 of seat board 24 and adapted to cooperate with apertures 47 in gusset plates 45. To this end, this invention contemplates a mounting plate 84 (Figures 4, 7 and 9). Plate 84 is made out of 12 gauge plate and is of substantially square configuration and provides two spaced mounting posts 86 flash welded thereto as best shown in Figure 9. Referring to Figure 9, each post 86 comprises a tapered shank 87 provided at one end with a support base 88 having a short cylindrical mounting boss 89. Boss 89 is adapted to snugly fit in a mounting hole 90 drilled laterally of the center in plate 84 and is of a length less than the thickness of plate 84. The mounting boss 89 is welded to plate 84 as indicated at 91 to rigidly connect posts 86 and plate 84.

The small end of shank 87 has integrally formed thereon a ball portion 92 adapted to cooperate with socket assemblies 93 secured to an end of the respective rods 85. Since each of the socket assemblies is identical, the following description will be sufficient for both.

Rods 85 each comprise cold roll tubular stock of $\frac{3}{4}$

inch outer diameter having a wall thickness of $\frac{1}{16}$ of an inch and an inner diameter of $\frac{5}{8}$ of an inch. One end of rod 85 is provided with a hollow plug 94 having a major outer diameter of $\frac{3}{4}$ inch and a reduced end portion 95 of substantial length adapted to have a forced fit in the end of rod 85. The end of rod 85 and end portion 95 are diametrically drilled and secured against relative movement by a rivet 96. As clearly seen in Figure 9, the wall thickness of plug 94 for an appreciable distance adjacent the junction of the major body and reduced portion 95 is of increased thickness forming thereby an outwardly facing annular shoulder 97 at the inner end of an internal bore of $\frac{5}{8}$ inch diameter threaded internally at its outer end. The peripheral wall of the thread portion of plug 94 close to its outer end is provided with a plurality of through holes 98 for a purpose to be hereinafter pointed out.

At one side of plug 94, the wall defining the $\frac{5}{8}$ inch internal bore is provided with a pear shaped through opening 99, the smaller end of which extends toward the inner end of the plug. The enlarged portion of opening 99 is sufficient to freely pass ball portion 92 of post 86 while the smaller portion will not.

The inner end of the $\frac{5}{8}$ inch bore is adapted to loosely receive in abutting engagement with shoulder 97 a solid cylindrical plug 101 the outwardly facing end of which is conically tapered inwardly at 102 to a diameter of $\frac{3}{8}$ inch. This tapered end has its end face shaped in the form of a ball-receiving socket 103 of a curvature to matingly engage ball 92. The length of the plug 101 is such that socket face 103 lies in a transverse plane slightly outwardly from the innermost end of the smaller portion of opening 99 so that, when ball 92 is entered through opening 99, axial movement of rod 85 may be effected to engage ball 92 in socket 103 behind the smaller portion of opening 99. With the parts in this position a second solid plug 104 having a similar configuration to plug 101 and a complementary ball socket and externally threaded to engage the threaded end of the $\frac{5}{8}$ inch bore is threaded into plug 93 until it matingly engages ball 92 between sockets 103. To this end, suitable diametrically crossing screw driver kerfs 105 are provided in the exposed end of plug 104. When the desired rolling fit is obtained between ball 92 and sockets 103, one of the screw driver kerfs is lined up with opposed holes 98 and a locking wire 106 is threaded therethrough to positively lock the structure in adjusted position.

It will be appreciated that this ball and socket connection not only operates as a universal connection within necessary limits but is adjustable through threaded plug 104 to take up for wear in use. Plate 84 at its four corners and at its center is drilled to receive rivets and when placed in the desired position centrally of leg support assemblies 31 provides a guide for drilling seat board 24 to accommodate rivets 75 which secure plate 84 and rods 85 permanently to seat board 24.

The opposite free ends of rods 85 are provided with quick connection couplings 109 adapted for ready association with gusset plates 45. Couplings 109 comprise a solid cylindrical member 111 of $\frac{5}{8}$ inch outer diameter and $1\frac{1}{8}$ inches in length having a squared end 110 and a bull nosed end, an annular peripherally protruding flange 112 beginning $\frac{3}{4}$ of inch inwardly from the squared end and a transversely extending counterbored passage 113 the axis of which is spaced $1\frac{1}{8}$ inches from the squared end. Flange 112 has an outer diameter of $\frac{3}{4}$ inch and an axial dimension of $\frac{1}{16}$ inch and is adapted, upon insertion of the squared end into rod 85, to abut the end of rod 85 and limit the extent of protrusion of the bull nosed end. While the described dimensions of plug 109 would effect a more or less press fit with rod 85, it is preferred that the rod end and telescoped portion of plug 109 be transversely drilled and positively connected by means of a rivet 114.

Passage 113 preferably has a major diameter of $\frac{5}{16}$ 75

inch extending substantially all the way through plug 109 leaving a terminally disposed, inwardly directed, annular shoulder 115 at one end having a through bore just slightly greater than $\frac{1}{4}$ of an inch. A pin-like button 116 having a flange at one end just slightly less than $\frac{5}{16}$ inch and a main body diameter of $\frac{1}{4}$ inch is disposed in passage 113 with the body portion protruding from the smaller end of passage 113 and the flanged end abutting the annular shoulder 115. A coil spring 117 disposed in passage 113 and compressed between the flanged end of button 116 and a spring retainer 118 held in the opposite end of passage 113 by peening over the edges of the passage as indicated at 119 resiliently biases button 116 to its protruding position.

Rods 85 in use are swung from the stored position, shown in Figure 7, by releasing clips 83, similar in all respects to clips 82 previously described, grasping the freed portion of the rods and swinging them on the universal connections provided through plate 84 and posts 86 toward the support position of Figure 4. At the same time freed leg support assemblies 31 are swung toward their support position and bull nosed ends of plugs 109 are entered into gusset plate openings 47. As leg assemblies 31 are forced home in their retainer clips 63, button 116 is pressed inwardly against the resistance of spring 117 to permit the gusset plates and leg assemblies to reach the support positions of Figure 4 at which time the protruding portion of pin 116 will be disposed on one side of gusset plate 45 and flange 112 of plug 109 on the other side as shown in Figure 10. With the ends of rods 85 and gusset plates 45 disposed as illustrated in Figure 10, movement of leg assemblies 31 in either direction from vertical supporting position will engage the faces of the gusset plates either with flange 112 or pin 116 and prevent further movement. It will be appreciated, therefore, that the reinforcing rods 85 form an adequate leg reinforcing and safety function preventing inadvertent movement of leg assemblies 31 from their desired support position even though retainers 63 should fail or a direct separating force be applied to free leg assemblies 31 from retainers 63.

As clearly seen in Figure 7, the front seat board reinforcing strip 25 is notched at two longitudinally spaced points indicated by numeral 121 throughout a substantial longitudinal distance. These notches form a part of finger openings 122 (Figure 1) provided for ready handling of the storage or shipping unit 17.

Back-table board assembly 16 comprises a back-table board 123 of plywood having reinforcing longitudinal edge portions in the form of fir strips 126 identical to strips 25 except the height which is preferably $1\frac{3}{4}$ inches instead of $2\frac{1}{4}$ inches. Since the dimensions of back-table board and its manner of construction are identical to that of seat board 24 except for the one dimension mentioned above, a detailed description thereof is not deemed necessary here. Suffice it to say that back-table board 123 provides an open-sided, open-ended recess 127 adapted to cooperate with recess 29 of seat board 24 when reinforcing portions 25 and 126 are abuttingly associated as shown in Figures 1 and 2 to form a hollow storage space within the box-like confines of the mating seat board/back-table board storage assembly unit.

As heretofore suggested, back-table board assembly 16 includes a support structure adapting back-table board 123 to serve selectively as a bench back or a table top surface in conjunction with seat board assembly 17. To this end, this invention provides two support post assemblies 129 best seen in Figure 8. Each post assembly includes a post made of 1 inch outer diameter cold roll steel or aluminum tubing having a long straight section 131 approximately $2\frac{1}{2}$ inches in length and an angularly disposed mounting section 132 approximately $7\frac{3}{4}$ inches in length. These two sections are joined by a curved section 133 formed on a 3 inch radius like the other curved tube sections. Section 133 is bent sufficiently to dispose sections 131 and 132 at an included angle of 105° in

order that back-table board 125 will have a proper inclination when serving as a bench back and yet be supported in a horizontal plane when used as a table top.

Referring for the moment to Figure 8, it will be seen that the free end of section 132 is journally supported in a sleeve-like member 134 similar to sleeve-like member 49 of the seat board assembly, retainer rings 135 being provided to properly locate the member 134 on section 132. The member 134, like the similar seat board assembly member 49, has a boss and journal portion, formed as heretofore described in connection with member 49, cooperating with a mounting plate 136 to form a prefabricated support post assembly 129.

Mounting plates 136 are identical in shape and dimensions to plates 61 and are provided with the same rivet drillings along their longitudinal edges. Plates 136 are also provided with journal openings 137 (Figure 4) identical in purpose to openings 59 heretofore described but differently located. In this latter connection holes 137 are located on a center disposed inwardly from the longitudinal edge 138 a distance of 2 inches and inwardly from the upper end 139 a distance of $3\frac{1}{2}$ inches. Each plate 136 is also provided with two lateral spaced drilled openings (not shown) to receive rivets 140 for securing retainer clips 67 and 141 in place on plates 136. These latter drillings, while suitably located as required, are in the prefabricated embodiment illustrated disposed four inches inwardly from the lower ends of plates 136 as seen in Figure 4 and 3 inches and $3\frac{3}{4}$ inches respectively inwardly from longitudinal edge 138. Clip 67 is identical in construction and operation to clip 63 heretofore described and a similar clip might be used in place of clip 141, except for the fact that the mounting of support post assemblies 129 on bench-table board 125 may possibly be slightly out of line with the mounting of leg support assemblies 31 on seat board assembly 17 thereby necessitating some slight variation in supporting position of one of the support posts in table supporting position. To provide for such adjustment, the loop 142 of clip 141 is shaped to encompass post section 132 throughout 180° only of its circumference and the terminal tip 143 extends parallel to the main body of clip 141 and its juncture with loop 142 is at the point of tangency between the plane of tip 143 and the portion of the loop remote from plate 136.

This clip construction permits the post associated with it to be disposed at a position between the main body portion of the clip and terminal tip 143 as well as in the loop 142 in order that lifting of back-table board 125 when in table top position will not dissociate post section 132 and clip 141. To prevent dissociation by forces applied lengthwise of the back-table board, the present invention also provides a leaf-spring member 144 having a securing section 145 riveted to support plate 136 and an upwardly inclined, laterally twisted portion 146 carrying a locking pin 147 adapted to engage in a mating hole 148 drilled in curved section 133 adjacent its point of juncture with support section 132 (see Figure 4) to locate the associated post in table support position.

Prefabricated post support assemblies 129, are assembled on back-table board 125 through use of predrilled spacers 149 in the manner heretofore described in connection with seat board assembly 17. Preferably the location for assembly of the final back-table support post assembly 129 is determined by placing back-table board 125 in table position and mounting both posts in their respective socket tubes 43 of seat board assembly 17 and then shifting spacer 149 to a position to properly cooperate with the mounting plate, the pin 147 having been previously engaged in its receiving hole 148 in its associated post. From then on assembly operations are identical to those previously described in connection with seat board assembly 17.

Referring to Figures 3 and 4 for the moment, it will be noted that back-table board 125 when in its bench-back

position is suspended from the support post universal connections with its lowermost reinforcing portion 126 contacting the support posts. To give greater sidewise stability to back-bench board 125 and assure its proper angular relationship to seat board 25, the lower reinforcing portion 126 is suitably notched as shown at 151 to freely receive the adjacent portions of post sections 131.

Referring to Figure 8, it will also be noted that both support post assemblies 129 are stored with their straight sections 131 extending generally inwardly toward the center of back-table board 125 and engaged by securing clips 87, similar to clips 82 and 83 previously described. Since the universal connections of post assemblies 129 permit only limited movement of support sections 132 out of parallelism to back-table board 125 and the left hand post must travel around the axis of the journal in plate 136 in a counterclockwise direction in order to properly enter clip 67, the upper back table board reinforcing portion 126 is longitudinally notched at 152 so the curved section 133 of the left hand post may swing freely through the necessary arc. A similar notch 152 is provided adjacent the other end of this reinforcing portion 126 and the similar notches 121 of seat board assembly 17 are matingly located to cooperate with notches 152 to together form the finger or hand-hold openings 122 previously referred to.

A back-table board of the character here described when supported in the previously described manner by support post assemblies will assume an offset relationship to seat board 24 as clearly seen from Figure 4. While this offset relationship is not too objectionable and permits end to end disposition of a plurality of benches to form continuous rows of seats for auditorium use or spectator seating around a room converted to gymnasium spectator sports events, a preferred form of this invention contemplates a support post assembly which will eliminate this offset relationship. Such a post assembly is illustrated in Figure 11 at 129A wherein the parts are identical to those previously described except for the post structures. As clearly seen from Figure 11, post sections 131 and 132 are connected by a goose neck section composed of curved section 133 as heretofore described and a second reversal bend section 154 also formed on a 3 inch radius as in the other bend sections. This goose neck connection maintains the previously described 105° angular relationship of post sections 131 and 132 but moves the mounting plate axis of the universal connection closer to the point of intersection of the planes containing the axes of post sections 131 and 132. As a consequence, back-table board 125, as viewed in Figure 4, will be bodily moved to the left into alignment with seat board 24 and in table position, as viewed in Figure 3, will result in back-table board 125 also being moved to the left to overlap seat board 24 somewhat more. This latter effect provides a further benefit since it moves the vertical force component due to weight of the table top and things supported thereby further to the left and further between the ground contact points of leg assemblies 31 thereby making the unit more stable insofar as weight supported by the table surface is concerned.

Ready usage of this article of furniture to furnish a seat-less school auditorium or gymnasium for lunch room use may be effected by arranging a multiplicity of the furniture pieces in end to end double row fashion with the table boards of the two rows in longitudinal abutting relation or grouping pairs of the furniture pieces in such abutting relation. In the first mentioned arrangement a longitudinally continuous table with attached oppositely facing seating would result while in the second arrangement a single table unit having oppositely facing seats would result.

Since exposed corners of plywood have a tendency to chip and separate, the present invention also contemplates capping the seat board and back-table board ends to ex-

tend the useful life of the product. This capping is preferably effected by spinning thin aluminum strip material around the ends of the seat board and back-table board before the reinforcing portions are assembled thereon to provide a C-shaped metal cap 161 as shown at the left 5 of Figure 4.

The present combination bench-table unit may also be provided with and readily store a seat cushion if desired. To this end, cushion 23 may be made of any suitable compressible substance such as foam rubber suitably covered. Cushion 23 may be secured to seat board assembly in any suitable manner but preferably employs securing straps 162 at each side of the back-table support posts, at each end and at two points at the front opposite the back straps. The free ends of each strap are preferably provided with 15 a female snap fastener element 163 (Figure 4) adapted to cooperate with mating male elements 164 (Figures 2 and 7) secured to the inner faces of reinforcing portions 25 and the ends of seat board inner face 28.

The invention may be embodied in other specific forms without departing from the spirit or essential characteristics thereof. The present embodiments are therefore to be considered in all respects as illustrative and not restrictive; the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A combined bench-table unit comprising an elongated seat board; edge reinforcing portions depending from one face thereof and forming therewith a recess; supporting leg structures of generally planar form enabling said leg structure to be stored within said recess; means connecting said leg structures to said one face enabling said structures to extend in a plane transverse to said face and parallel to the width of the seat board; a combined back-table board; edge reinforcing portions depending from one face thereof and forming therewith a recess, one of said reinforcing portions being notched at one point at least along its free edge, said back-table board and reinforcing portions being of equal dimensions to those of the seat board; a support structure for said back-table board comprising tubular posts each having a main support portion and an angularly offset terminal portion, said leg structure having sockets removably, pivotally receiving the free ends of said main support portions of said posts, means spaced longitudinally of the recess face of said back-table board universally connecting the free ends of said offset terminal portions of said posts to said back-table board for swinging movement to a stored position within said recess and to a table or seat back position whereby said seat board and back-table board, with their respective support structures in stored position and their edge reinforcing portions cooperating in abutting relation, cooperate to form a box-like storage and transfer unit with all support structure enclosed; and releasable means for connecting and holding the seat board and back-table board edge reinforcing portions together in said abutting relation.

2. The storage unit of claim 1 together with an apertured gusset plate secured to each leg structure; a pair of leg support reinforcing rods having respective ends formed with retractable pins and axially spaced annular flanges spaced to rigidly receive therebetween a portion of the respective gusset plates when the terminal portions of said ends and said retractable pins are passed through the respective apertures in said gusset plates; and their opposite ends connected to said one face of said seat board substantially at the center thereof through universal connections adapting said respective reinforcing rods to be disposed, when uncoupled from said gusset plates, in stored position within the confines of said seat board storage recess in generally parallel relation to said one face.

thereof; and a securing clip for each of said reinforcing rods to receive its respective rod in its stored position and retain it in stored position.

3. A seat board assembly for a combined bench-table comprising an elongated seat board composed of relatively thin, bendable composition board; a reinforcing strip secured to each longitudinal edge of said seat board comprising a member of a length equal to the length of said seat board and a height substantially greater than the thickness of said seat board, said reinforcing strips depending from one face of said seat board to define a downwardly opening, open-ended leg structure receiving space of a depth sufficient to receive therein foldaway leg structures; and a leg structure assembly disposed inwardly from each end of said seat board and each comprising spacer means of elongated rectangular configuration disposed with its longitudinal axis transversely of said seat board between said reinforcing strips and having adjacent one end a through opening spaced from said seat board, a sleeve-like journal member having a right angularly disposed boss terminating in a cylindrical portion of reduced size journallingly cooperating with and having its end protruding through the opening in said spacer means, a washer secured to the protruding end of said cylindrical portion adjacent to and cooperating with the surrounding face of said spacer means to retain said sleeve-like member in journalling cooperation in said opening, means for securing said spacer means in assembled relation to said one face of said seat board in predetermined position, and a retainer member secured to said spacer means at a location remote from said sleeve-like journal member and having means to engage a portion of said leg structure when disposed in supporting position to secure said leg structure in supporting position, said leg structures being formed of angularly related cylindrical tubular elements one of which is a straight section of a length less than the distance between said reinforcing strips and provides at one end the journalled portion received by said sleeve-like journal member and another of which is angularly inclined to said one tubular element and is disposed in supporting position of said leg structures in a common plane with said one tubular element with an axis inclined to said seat board with an open end disposed beyond said one end of said straight section within the confines of the adjacent reinforcing strip and said seat board being provided opposite said open end with an inclined opening to permit entry of a support rod of a cooperating back board-table board into said other tubular element to be supported thereby.

4. The combination defined in claim 3 wherein said inclined seat board opening is provided with a metallic bushing adapted to provide a wear surface to eliminate undue wear of the seat board in use.

5. A combined back-table board support for a convertible bench-bench table having a bench leg socket for receiving said back-table board support comprising a support post having a first straight support section adapted to be received in said leg socket and a second angularly related straight section adapted to be universally connected to said back-table board at one end and a goose neck connection between said post sections lying in the plane containing the axes of said straight sections and so positioning the second section in relation to the first section that a line extended along the axis of the first section will intersect the approximate midpoint of the second section.

6. A back-table board assembly for a combined bench-bench table comprising a planar back-table board elongated in one direction; reinforcing members of a thickness substantially greater than the thickness of said back-table board extending along the longitudinal edges to reinforce said back-table board longitudinally, said reinforcing members protruding a substantial distance beyond the bottom surface of said back-table board to define between them an open storage recess; a support post struc-

ture for said back-table board comprising two post elements of L-like form respectively universally connected at one end of the short arms of the post elements to said bottom surface of said back-table board at longitudinally spaced transversely aligned points adapting said post elements to be stored within said storage recess in parallel relation to said bottom surface with the long arms of the post elements extending generally longitudinally of said back-table board and adapted to be swung upwardly around the short arm axis of said universal connections 10 and then swung in an arcuate path around the other right angularly disposed axis of said universal connections to position the long arms of the post elements selectively in one of two support positions substantially normal to the longitudinal axis of said back-table board; at least one 15 notch in one of said reinforcing members transversely spaced from the connection of one of said posts of a length sufficient to freely pass the short arms of the post element when swung in its respective arcuate path; and means at spaced points on said back-table board and projecting beyond said bottom surface thereof to engage the respective post elements and maintain them in one of their 20 respective support positions.
